INCANDESCENT ELECTRIC LAMP

Alexandre Van Dyck, Brussels, Belgium

Application November 12, 1937, Serial No. 174,223
In Belgium November 18, 1936

12 Claims. (Cl. 176—40)

This invention relates to incandescent electric lamps and the like, and concerns in particular the construction of their illuminant bodies or filaments.

The invention has for its main object to provide a novel method of forming metallic illuminant bodies of refractory materials for incandescent electric lamps and the like, affording a luminous efficiency at least equal to that of illuminant bodies constituted by single or double coiling of the usual filaments, while avoiding the disadvantages of these last illuminant bodies.

The illuminant bodies made according to the invention are characterized in that they are obtained by means of filaments constituted with fine multiple wires, made of refractory materials, coiled, woven, plaited, superposed or assembled by any convenient means around a mandrel of suitable cross section (or an imaginary core), the mandrel being for example and preferably cylindrical; these filaments are presented therefore in the form of a hollow wire composed of multiple elements.

When coiled into a single helix, the hollow filaments constituting the invention form an apparently thick body of the dimensions customary in the art, and having a luminous efficiency at least equal to that of coiled-coil filaments.

The hollow filaments made according to the invention allow of obtaining very easily any desired thickness of wall. These filaments approximate therefore homogeneous hollow filaments, made in one piece, the manufacture of which would present insurmountable difficulties by reason of the nature of the material employed.

In the case of helical coiling of the hollow filaments made according to the invention, the elements which compose them enjoy a certain reciprocal freedom so that the very objectionable stresses and deformations experienced in the single or double helices formed with a single wire, as explained above, are largely, if not wholly, avoided.

For the same reasons, the waste during the mechanical operation of coiling will be greatly reduced, if not suppressed.

There may be adopted, according to the invention, for the manufacture of the hollow filament, the most varied arrangements of the component wires or filaments. Thus, for example, series of component elements or wires will be placed either along parallel helices of long pitch, or along right and left-handed helices or helices of different pitch, so as to obtain crossings of the elements and to produce a sort of plaiting.

The accompanying drawing represents diagrammatically three examples of the formation of hollow filaments according to the invention.

In Fig. 1, *a* is the mandrel, which supports four lengths of wire, numbered from 1 to 4, as constituent elements of the filament. For greater simplicity, each of these lengths of wire is shown as consisting of a single wire but it might comprise several wires.

The lengths of wire 1 and 2 are wound along parallel helices, for example right-handed, as shown, and the lengths of wire 3 and 4 along parallel helices of opposite pitch to the first two, for example left-handed, as shown, the pairs of helices crossing one another.

Figs. 2 and 3 represent respectively in elevation and in plan a filament composed of multiple lengths of wire wound in multiple helices opposed so as to form a plaited sheath around the mandrel *a*.

More generally, recourse may be had to all the known arrangements adopted for the manufacture of continuous plaited sheaths, which will allow in particular of utilizing existing machines fed with wires made of suitable refractory metals.

The manufacture of the hollow filaments according to the invention can be effected upon a mandrel of suitable shape, for example cylindrical, which will be either removed after completion of the hollow filament or else maintained in this latter. In the first case, there will be used a mandrel made of materials known in the lamp industry and adapted to be eliminated, chemically or otherwise, leaving the material of the illuminant body unattacked, such as wires of brass, copper, steel, or even refractory metals such as molybdenum. In the second case, recourse may be had to mandrels made of infusible and refractory materials, bad conductors of electricity, but adapted to emit luminous radiation, like asbestos for example.

The fine wires or component elements of the hollow filaments can be of any cross-section whatever, circular, oval, rectangular or other.

For the manufacture of the helices, the hollow filament made as explained above can be coiled to shape, retaining the mandrel which has served for making it, upon a second mandrel of suitable cross-section (or around an imaginary core) which may have the same properties as the first mandrel. After the coiling of the helices, these two mandrels (or only one of the two) will be eliminated in the manner explained above or maintained in place.

grammatically and by way of example a hollow filament, made according to the invention, and coiled upon a mandrel *b*, *a* being the mandrel which has served for the formation of the hollow body or wire proper.

The helical coiling of the hollow filament can be effected upon the machines currently in use for the manufacture of the second helix of the known coiled-coil filaments, but with infinitely greater facility, having regard to the firmer and more homogeneous nature of the body coiled.

Further, in the manufacture of the hollow illuminant filaments, according to the invention, intended to be coiled like helices, account may be taken of the stresses which arise during this coiling, by means of a suitable arrangement of the component elements. Also provision may be made for a suitable distribution of the constituent elements of the hollow filament in order to obtain such distribution as desired of the radiation in the helices formed; it is clearly possible in this way to increase further the specific efficiency as well as the length of life of the illuminant bodies.

By way of indication, there will be given hereafter a comparative example of an illuminant body of the usual kind formed by a single wire coiled as a helix, which is in turn coiled helically, and a hollow filament constituted according to the invention and coiled into a helix.

The two cases refer to an illuminant body made of tungsten for a gas-filled lamp of 100 watts for a voltage of 110 volts, the same weight of tungsten having been utilized for both.

A. Single filament coiled as a double helix.
 Wire employed: diameter 0.065 mm.
 Length of the straight filament 497 mm.
 First or primary helix:
 Diameter of the mandrel 0.120 mm.
 Number of turns 855
 Pitch of the helix 0.100 mm.
 Length of the helix 97 mm.
 Second or secondary helix:
 Diameter of the mandrel 0.550 mm.
 Number of turns 39
 Pitch of the helix 0.250 mm.
 Length of the helix 19.5 mm.
 Total emission surface 65.8 sq. mm.

By the expression "total emission surface" there is to be understood the enveloping surface of the coiled coil or double helical filament; this imaginary surface constitutes in accordance with the recognized theory of luminous radiation the true emission surface of the filament.

B. Hollow filament made according to the invention and coiled as a helix.
 Wire employed 0.012 mm.
 Number of elements or wires 30
 Plaiting mandrel: diameter 0.120 mm.
 Diameter of the hollow filament (plaited sheath) 0.168 mm.
 Length of the hollow filament (straight plaited sheath) 497 mm.
 Diameter of the mandrel for coiling into a helix 0.750 mm.
 Number of turns 173
 Diameter of the helix 1.082 mm.
 Length of the helix 51 mm.
 Total emission surface 173 sq. mm.

It is easy to deduce from the above data that the sectional area of passage for the current is substantially the same in the two cases and

whereas the same weight of tungsten has been utilized, the total emission surface in the lamp with a hollow filament made according to the invention and wound as a helix is about 2½ times greater than in the case of the single filament coiled as a double helix.

It will be observed moreover that since the single filament of the double helix is replaced by a large number of elementary wires, the defects which might be exhibited by one or other or even by several of these wires will not involve the rupture of the illuminant body.

If for example, which is relatively frequent, the single filament of the double helix is badly gauged, a vaporization of the material will be produced in the thinnest zone, and the illuminant body will be destroyed rapidly by the consequent rupture of the filament.

In the hollow filament made according to the invention and coiled as a helix, a defect of this kind, even if it were to affect several of the elementary wires, could have only a very relative influence, owing to the fact that the aggregate sectional area will be practically unaltered so that the destruction of the illuminant body cannot result therefrom.

The mounting of the illuminant bodies formed with hollow filaments according to the invention can be effected just as in the case of an ordinary filament of the plain coiled or coiled-coil type, that is to say by pinching to the two electrodes and arranged upon suitable supports, for example consisting of molybdenum wires.

What I claim is:—

1. In the art of incandescent electric lamps, a filament consisting of an elongated hollow body having its surface formed of refractory metal wires, said body being coiled into a compact shape to constitute the filament.

2. In the art of incandescent electric lamps, a filament consisting of an elongated hollow body having its surface formed of refractory metal wires plaited together, said body being coiled into a compact shape to constitute the filament.

3. In the art of incandescent electric lamps, a filament consisting of an elongated hollow body having its surface formed of refractory metal wires, said body being coiled into helical form to constitute the filament.

4. In the art of incandescent electric lamps, a filament composed of refractory metal wires arranged as coaxial helices of long pitch, said wires being plaited together to form a sleeve, and said sleeve being coiled as a helix of short pitch to constitute the filament.

5. In the art of incandescent electric lamps, a filament composed of refractory metal wires arranged as coaxial helices of long pitch, said wires being woven together to form a sleeve, and said sleeve being coiled as a helix of short pitch to constitute the filament.

6. In the art of incandescent electric lamps, a filament composed of refractory metal wires, a group of said wires being arranged as parallel right-handed helices of long pitch, another group of said wires being arranged as parallel left-handed helices of long pitch, the wires of said groups being intertwined to form a plaited tubular sleeve, and said sleeve being coiled as a helix of short pitch to constitute the filament.

7. In the art of incandescent electric lamps, a filament in the form of a tubular sleeve coiled into a helix with adjacent coils in close relation to one another, the walls of said sleeve consisting of plaited wires of refractory metal.

8. An incandescent electric lamp filament, consisting of a plurality of relatively short and fine wires of refractory metal, said wires being plaited together to form a sleeve with the wires 5 extending in helices of long pitch, and said sleeve being coiled as a helix of short pitch to constitute the filament.

9. An incandescent electric lamp filament, consisting of a plurality of relatively short and fine 10 wires of refractory metal, said wires being woven together to form a sleeve, and said sleeve being coiled as a helix of short pitch to constitute the filament.

10. An incandescent electric lamp filament, 15 consisting of a plurality of relatively short and fine wires of refractory metal, said wires being plaited together around a mandrel to form a sleeve with the wires extending in helices of long pitch, and said sleeve being coiled around another 20 mandrel as a helix of short pitch to constitute the filament.

11. The method of making an incandescent

electric lamp filament, which comprises the steps of drawing fine wire in refractory metal, cutting lengths of said wire, assembling a plurality of lengths of said wire around a mandrel, assembling said lengths to form a tubular sheath, removing 5 said sheath from the mandrel, and coiling said sheath around a mandrel to constitute a closely coiled hollow body of elongated form having its walls formed of said refractory metal wires.

12. A 100-watt filament for a 110 volt lamp, 10 consisting of approximately 30 tungsten metal wires plaited into the shape of a sleeve, the diameter of said wires being approximately 0.012 millimeter, the diameter of said sleeve being approximately 0.168 millimeter, and the length of 15 said sleeve being approximately 497 millimeters, and said sleeve being then closely coiled to form a helix of short pitch, the diameter of said helix being approximately 1.082 millimeters, and the length of said helix being approximately 51 milli- 20 meters.
